E. J. W. RAGSDALE

LATCH MECHANISM

Filed Dec. 28, 1923

UNITED STATES PATENT OFFICE.

EARL J. W. RAGSDALE, OF NORRISTOWN, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

LATCH MECHANISM.

Application filed December 28, 1923. Serial No. 683,148.

My invention relates to improvements in latch mechanism and has to do, more particularly, with latch mechanism of the type employing a swinging latch bolt, such as is used in the doors of automobile bodies, and in similar situations.

The principal object of my invention is to provide a latch construction which is simple in construction, is composed of few parts, is economical to construct, is easy to assemble and apply, and is efficient in use.

A further object of my invention is to provide a latch mechanism in which the same spring is employed to project the swinging bolt and also to restore the roll-back to normal position after it has been moved therefrom.

A further object of my invention is to provide a latch mechanism of type referred to having an improved means for mounting the swinging latch bolt, whereby the bolt and the operating mechanism therefor may be assembled as a unit on a retaining member and the unit assembly mounted on the base plate very quickly and conveniently.

A further object of my invention is to provide a latch mechanism, including a swinging bolt and a roll-back for actuating said bolt, having an improved and simplified connection between the roll-back and the bolt.

Further objects, and objects relating to details and economies of construction and operation, will definitely appear from the detailed description to follow. In one instance, I accomplish the objects of my invention by the devices and means set forth in the following specification. My invention is clearly defined and pointed out in the appended claims. A structure constituting a preferred embodiment of my invention is illustrated in the accompanying drawing, forming a part of this specification, in which:

Fig. 1 is a view, in elevation, of a latch mechanism embodying my invention, the retaining plate being broken away to show the roll-back and its connections.

Fig. 2 is a sectional view through said latch mechanism, taken on the line 2-2 of Fig. 1.

Fig. 3 is a top plan view of the latch mechanism, and

Fig. 4 is another view of the latch mecha-

nism, in top plan, with the retaining plate 55 in section to show the roll-back and the connections between the roll-back and the latch bolt.

In the drawing, the same reference numerals refer to the same parts throughout the several views, and the sectional view is taken looking in the direction of the arrows at the ends of the section lines.

In carrying out my invention in one practical embodiment thereof, I propose to 65 mount the latch bolt upon a retaining member, together with the means employed to actuate said bolt, thereby effecting a unit assembly of the bolt and its actuating means wherein the parts may be quickly and easily 70 assembled ready for mounting as a unit on a base plate for application to a door. I also propose to connect the latch bolt and the roll-back of the latch mechanism by a very simple but efficient connection whereby 75 when the roll-back is rotated in either direction from its normal position, the latch bolt is swung into its retracted position. I also propose, in accordance with my invention, to employ the same spring tension 80 device which normally tends to project the latch bolt, to also resist the rotation movements of the roll-back in either direction from its normal position.

Various specific arrangements may be devised for carrying out these general objects and purposes of my invention. While, therefore, I have shown, and will now describe one practical embodiment of my invention, I do not desire to be limited or restricted, 90 in the broadest scope of my invention, to the exact details and arrangements shown.

In the particular embodiment of my invention, as shown in the drawing, I employ a retaining member, 13, upon which the 95 swinging latch bolt, 23, is mounted. In the illustration arrangement shown, the retaining member is provided with arms, or portions, 21, spaced apart from each other and extending forwardly to form supports 100 for the pivot pin, 22, of the latch bolt. The side wall of the retainer member, 13, is formed with a bearing in which is journaled one end of the hub, 31, of the roll-back, the arms, 34, of the roll-back extending in opposite directions from each other from the hub, 31. Suitable connections intermediate the roll-back and the latch bolt serve to

retract the latch bolt from its normally projected position when the roll-back is rotatively actuated in either direction. The means shown for this purpose in the illustration embodiment of my invention as shown, consists of a rod or wire having a loop formation, the laterally bent free ends 27 of which are disposed, respectively, to project in opposite direction through the side walls, 25, of the latch bolt into the interior of said latch bolt. From the laterally bent end portions, 27, of this wire, or rod, extend the parallel leg portions, 26. These leg portions are laterally off-set or bent to form shoulders indicated at 27^a, which shoulders engage behind the rear vertical walls of the roll-back, so that when the roll-back is rotatively moved in either direction, one or the other of the shoulders, 27, will be shifted in a direction to cause a pull to be exerted on the latch bolt to draw the latter into its retracted position. This connection intermediate the roll-back and the latch bolt may be guided in its shifting movement in many different ways. A simple arrangement is shown wherein rearwardly of the shoulders, 27^a, the side portions of the wire or rod are slightly converged towards each other, as indicated at 28, and thence rearwardly are formed into the loop portion, 30, the legs of which pass through notches formed in the edges of the rear wall, 14, of the retainer member, 13. By this construction and arrangement, a very simple retracting connection is provided intermediate the roll-back and latch bolt, consisting of a single bent wire or rod. Also, as will be readily seen, this latch bolt retracting connection is retained in proper position and is guided in a very simple and efficient manner.

The latch bolt is normally maintained under yielding tension in projected position, and, in accordance with my invention, I propose to employ the same tension means which yieldingly maintains the latch bolt in projected position to also impose a yielding tension on the roll-back to normally retain it in normal position. This result may be accomplished in various ways. A simple arrangement is shown wherein I employ a spring, the ends of which are coiled about the pivot pin, 22, of the latch bolt, as indicated at 36, the extremities, 37, of the coils, 36, extending into the interior of the latch bolt and engaging behind the ends, 27, of the bolt retracting members, 26, as clearly shown in Fig. 2. The portions of the spring which extend rearwardly from the coils, 36, are brought into parallel relation as shown at 38, and then are formed into a loop portion, 39, which is arranged to seat in a groove, 35, formed in the forward surface of the roll-back arms, 34. With this construction and arrangement, it

will be readily seen that when the parts occupy their normal position, the latch bolt is yieldingly pressed into its projected position while at the same time the roll-back is yieldingly maintained in its normal or 70 neutral position, the same spring performing this double function. It will also be seen that when the roll-back is rotatively actuated in either direction from its normal position to retract the latch bolt, such 75 rotative actuation is against the tension of the spring, since it effects a compression of the loop portion of the spring, which tension is exerted to restore the roll-back to its normal or neutral position. Also it will be 80 seen that as the latch bolt is retracted, it is against the tension of the extremities, 37, of the spring acting upon the bent ends, 27, of the bolt-retracting connections.

The latch bolt and its retracting and tensioning devices are all mounted on and carried by the retainer member, 13, and, therefore, can be quickly, easily and readily assembled as a unit upon said member. In order to effect the application of this unit 85 assembly to a door, I prefer to mount the retainer member, 13, with the latch bolt and its associated parts assembled thereon, upon a base plate, 10, which is designed to be applied to the door. The mounting of the 90 retainer member, 13, upon the base plate, 10, may be effected in any desired manner. A simple arrangement is shown as one practical way wherein the edge, 15, of the rear wall, 14, of the retainer, 13, is inserted 95 through a slot in the base plate and then upset as indicated at 16, while the forward extremities, 19, of the arms, 21, extend through slots, 20, formed in the front edge flange, 11, of the base plate. If desired, the side 100 edge of the arms, 21, may also be provided with projecting portions, 17, which fit into slots, 18, in the base plate, 10.

The base plate, 10, is formed with the edge flange, 11, to facilitate the application and mounting of the latch mechanism upon the door, and, if desired, the extreme edge of the flange, 11 may also be turned laterally from said flange, as indicated at 12, to afford a means for supporting the base plate in 110 position on the door. The flange, 11, of the base plate is formed with an opening through which the latch bolt works in the usual manner. The end wall, 24, of the latch bolt is formed on an arc which is concentric with the axis of the pivot pin, 22, about which the latch bolt swings.

The base plate, 10, is formed with a journal bearing to receive the journal portion, 32, of the roll-back hub, 31.

The roll-back may be actuated in any suitable or well known manner, as for instance, by the spindle, 41, and handle, 42, therefor.

It will be observed that I have simplified 120 the construction of the latch mechanism very 130

materially, and reduced the number of parts. It will be noticed, particularly, that in place of the two springs customarily used with latches of this construction, I have devised a single spring which does the work of both of the springs formerly used. It will also be noticed that I have provided a very simple and cheap operating connection between the latch bolt and the roll-back, which has very little surface in frictional contact with other parts, so that the friction of moving parts is greatly reduced, and the weight and cost of the latch mechanism is lessened materially.

I am aware that the latch mechanism, illustrated in these drawings, may be changed considerably without departing from the spirit of my invention, and, therefore, I claim my invention broadly, as indicated by the appended claims.

Having thus described my invention, what I claim as new and useful and desire to secure by Letters Patent is:

1. A latch mechanism comprising a swinging latch bolt, a roll-back, resilient means directly engaged with said latch bolt and said roll-back to project the former and to maintain the latter in its normal or neutral position and means for rotating said roll-back in either direction to retract said latch bolt against the resistance of said resilient means.

2. A latch mechanism comprising a swinging latch bolt, resilient means directly engaging said latch bolt and adapted to project the same, said means being provided with an enlarged loop portion, a roll-back maintained in neutral position through direct engagement with said loop portion of the resilient means, and means interconnecting said latch bolt and said roll-back whereby upon rotation of the latter in either direction the former is retracted.

3. A latch mechanism comprising a swinging latch bolt, a roll-back, resilient means directly engaging said latch bolt at the free ends thereof, the portion of said resilient means intermediate the free ends being in sliding engagement with the said roll-back whereby when the roll-back is rotated in either direction to retract the latch bolt said resilient means tends to restore said roll-back to its normal or neutral position.

4. A latch mechanism comprising a swinging latch bolt, a roll-back, resilient means directly engaging said latch bolt at the free ends thereof, the portion of said resilient means intermediate the free ends being in sliding engagement with the said roll-back whereby upon rotation of said roll-back in either direction the latch bolt is retracted against the resistance of said resilient means, while at the same time said resilient means tends to restore the roll-back to its normal or neutral position.

5. A latch mechanism comprising a swinging latch bolt, a pivot pin on which said latch bolt is mounted, a roll-back, connections between said roll-back and said bolt, means for rotating said roll-back, and a spring coiled around said pivot pin and having one portion acting on the latch bolt to project the same, and another portion acting on said roll-back to restore it to normal position.

6. A latch mechanism comprising a swinging latch bolt, a pivot pin on which said latch bolt is mounted, a roll-back, connections between said roll-back and said latch bolt, and a spring coiled around said pivot pin, and having a loop engaging said latch bolt to project the same.

7. A latch mechanism comprising a swinging latch bolt, a pivot on which said latch bolt is mounted, a roll-back, connections between said roll-back and said latch bolt, and a spring coiled around the latch bolt pivot, and having loops extending rearwardly and engaging the forward edge of the roll-back to restore the same to normal position.

8. A latch mechanism comprising a swinging latch bolt, a pivot pin on which said latch bolt is mounted, a roll-back, connections between said roll-back and said latch bolt, a spring coiled around said latch bolt pivot, and having a loop portion engaging the latch bolt to project the same, and rearwardly extending loops engaging the forward face of the roll-back to restore the same to normal position.

9. A latch mechanism comprising a swinging latch bolt, a roll-back, and connections between said latch bolt and roll-back comprising a wire bent to form a yoke and having shoulders formed therein in position to be engaged by the arms of said roll-back.

10. A latch mechanism comprising a swinging latch bolt, a roll-back, and connections between said roll-back and latch bolt comprising a wire bent to form a yoke embracing said roll-back and having its forward ends bent laterally into engagement with the side walls of the latch bolt, said yoke being bent to form shoulders engageable by the arms of said roll-back.

11. A latch mechanism comprising a base plate, having a flange at one edge thereof provided with an opening for the bolt, a swinging latch bolt, a pivot on which said latch bolt is mounted, a roll-back, and a spring coiled around the pivot and provided with a loop engaging said latch bolt to project the same, and having rearwardly-extending loops engaging the forward face of the roll-back to restore the same to normal position.

12. A latch mechanism comprising a base plate, a swinging latch bolt, a roll-back, and operating connections between said latch

bolt and roll-back comprising a wire bent to form a yoke, having its forward ends connected to the sides of said latch bolt, its rear end formed into a loop slidably guided on the base plate, and its intermediate portion formed into shoulders engageable by the arms of said roll-back.

13. A latch mechanism comprising a base plate, a swinging latch bolt, a roll-back journaled on said base plate, and connections between said roll-back and latch bolt comprising a wire bent to form a yoke, having its forward ends bent laterally and extending through holes in the side walls of said latch bolt, the intermediate portions of the legs of said yoke being bent to form shoulders for engagement with the arms of said roll-back, and the rear portion of said loop being slidably guided on said base plate.

14. A latch mechanism comprising a base plate, a swinging latch bolt, a roll-back journaled on said base plate, a retaining member mounted on said base plate in which the roll-back is also journaled, said retaining member having an end wall extending into and connected with said base plate, and connections between said bolt and roll-back comprising a wire bent to form a yoke, having its forward ends connected with the side walls of said latch bolt, the intermediate portions of the legs of said yoke bent to form shoulders engageable by the arms of said roll-back, and the rear portion of said yoke being slidably mounted on the base plate and guided by the end wall on said retaining member.

15. A latch mechanism comprising a base plate, a swinging latch bolt, a rotatable roll-back, operating connections between said roll-back and latch bolt, comprising a wire bent to form a yoke, and having the ends of the legs of said yoke connected to the side walls of said latch bolt, the intermediate portions of said legs bent to form shoulders engageable by said roll-back, and the rear portion of said loop slidably guided on said base plate, and a spring having a portion acting on the latch bolt to project the same, and another portion acting on the forward face of said roll-back to restore it to normal position.

16. A latch mechanism comprising a base plate, a swinging latch bolt, a roll-back journaled on said base plate, operating connections between said latch bolt and roll-back consisting of a wire bent to form a yoke, the forward ends of the legs of said yoke being bent laterally and extending through holes in the side walls of said latch bolt, the intermediate portions of said legs being bent to form shoulders engageable by said roll-back, and a spring having a loop portion engaging the forward ends of said yoke adjacent the side walls of the bolt, and another loop

portion engaging the forward face of the roll-back to restore it to normal position.

17. A latch mechanism comprising a base plate, a pivot pin mounted thereon, a swinging latch bolt mounted on said pivot pin, a roll-back, operating connections between said latch bolt and roll-back comprising a wire bent to form a yoke and having its forward ends bent laterally and projecting through holes in the side walls of said latch bolt, and intermediate portions of the legs of said yoke bent to form shoulders engageable by the arms of said roll-back, and a spring coiled around the pivot and having a loop engaging the laterally-turned ends of said yoke, and another loop engaging the forward face of said roll-back to restore it to normal position.

18. A latch mechanism comprising a bolt, a roll-back, operating connections between said bolt and said roll-back, said roll-back being provided with a groove in the forward face thereof, and a spring having a portion positioned in said groove and engaging said roll-back to restore the same to normal position.

19. A latch mechanism comprising a swinging latch bolt, a roll-back having a groove in the forward edge thereof, operating connections between said bolt and said roll-back, and a single spring engaging said latch bolt to project the same, and engaging in the grooved forward edge of said roll-back to restore the latter to normal position.

20. A latch mechanism comprising a base plate, having a flange at one edge thereof provided with a bolt opening therein, a retaining plate provided with flanges at the sides and rear ends thereof, the edges of said flanges engaging the base plate and supporting the retaining plate in spaced relation thereto, the side flanges of said plate extending forwardly forming arms, a pivot pin carried by the forward ends of said arms, a latch bolt working in said bolt opening and journaled on said pivot pin, a roll-back journaled in said base plate and said retaining plate, connections between said bolt and said roll-back, and a spring coiled on said pivot pin and engaging the bolt to project the same and the roll-back to restore the latter to normal position.

21. A latch mechanism comprising a swinging latch bolt, a roll-back, and connections between said latch bolt and said roll-back comprising a wire bent to form a shoulder adapted to be engaged by said roll-back to retract the latch bolt.

22. A latch mechanism comprising a swinging latch bolt, a roll-back having arms extending laterally from the sides thereof and connections between said latch bolt and roll-back comprising a single wire adapted to be engaged by either of the arms of the roll-back whereby to retract the latch bolt

upon rotation of the roll-back in either direction.

23. A latch mechanism comprising a swinging latch bolt, a pivot pin on which said latch bolt is mounted, a roll-back, and a single spring having the free end portions thereof coiled around said pivot pin and

having its intermediate portion bowed for symmetrical disposition with respect to said roll-back whereby upon displacement of said roll-back in either direction said spring tends to restore the same to normal position. 10

In testimony whereof, I affix my signature.

EARL J. W. RAGSDALE.
